Primary Examiner — Cathron Brooks*Assistant Examiner* — Sharon S Oum(74) *Attorney, Agent, or Firm* — Head, Johnson, Kachigian & Wilkinson, PC(57) **CLAIM**

The ornamental design for a chimney pot, as shown and described.

DESCRIPTION

FIG. 1 is a front perspective view of my design;
 FIG. 2 is a front view, the rear view, left side and right side views are mirror images thereof;
 FIG. 3 is a top view thereof; and,
 FIG. 4 is a bottom view thereof.

The features shown in broken lines in the drawings form no part of the claimed design.
